UNITED STATES PATENT OFFICE.

JOHN E. WOODBURY, OF WORCESTER, MASSACHUSETTS.

METHOD OF PRINTING.

1,318,943.

Specification of Letters Patent. Patented Oct. 14, 1919.

Application filed January 16, 1918. Serial No. 212,010.

To all whom it may concern:

Be it known that I, JOHN E. WOODBURY, a citizen of the United States, residing at Worcester, in the county of Worcester and State of Massachusetts, have invented a new and useful Method of Printing, of which the following is a specification.

This invention relates to intaglio printing. It is especially made for the purpose of facilitating printing from intaglio plates, especially on moistened paper. In practice, I have found that when printing on moistened paper from intaglio plates, containing both illustrations and reading matter, the broad cuts in the intaglio plate, especially those forming the letters, will receive continually increasing projections from the soft blanket as the same is compacted. This tends increasingly to cause the ink to be forced out at the edges of the cuts and to make inferior work.

One of the objects of this invention is to provide for remedying this difficulty and especially to provide a method whereby the operator can control the operation in accordance with the conditions existing. Further objects of the invention will appear hereinafter.

Reference is to be had to the accompanying drawings, in which—

Figure 1 is a side view of a plate printing press in which this invention can be carried out;

Fig. 2 is a front elevation of the same; Fig. 3 is a side view of a portion thereof on enlarged scale;

Fig. 4 is a front elevation of the counter on a larger scale than that shown in Fig. 2, slightly modified;

Fig. 5 is a horizontal sectional view on the line 5—5 of Fig. 4;

Fig. 6 is a plan of part of a modified construction, and

Fig. 7 is a front elevation of the same also showing the construction illustrated in Figs. 4 and 5.

The subject matter illustrated in Figs. 1 to 3, is divided out of my Patent No. 1,255,263 granted Feb. 5, 1918, on a counter for intaglio presses, filed July 17, 1913.

The invention is shown in the first three

figures as carried out on a well known type of intaglio press having a frame 10, driving shaft 11, and feed mechanism 12 for driving a roll 13 which moves a web of paper along 55 for wiping off the plate. This press also as usual is provided with a counter support 15, and a plunger 16, details of which will not be described as they do not constitute a part of this invention.

On the counter support is the usual counter block 20 carrying the counter 19. In addition to the ordinary construction the counter is provided with a second portion 21 which forms a part of the counter, and 65 is movably mounted with respect to the main part thereof. This is shown as consisting of a blanket or the like formed of suitable blanket material. It is shown as being mounted on a rectangular frame 22 70 which surrounds the counter. This frame is shown as made up of horizontal sides and ends in Fig. 2 but they are arranged on edge on the second sheet.

This blanket is connected with the frame 75 by clamps 24 which are held by bolts.

The blanket and blanket frame are held normally toward one side of the press by a spring 25 which in this case is shown as also supporting the end of this frame. The tendency of the spring is to force the counter-frame to the right in Figs. 2 and 4.

Connected with the other end of the frame is a rod 26 which is pivoted on a crank 27 on a vertical shaft mounted in a 85 bearing 28 on the frame. This shaft is provided with an arm 29 for operating it. The arms 27 and 29 and the shaft can be made conveniently of an integral piece of wire bent into the shape shown. The arm 29 is 90 intended to be operated by a link 30 which is provided with a stud 31 connected by a link 32 with a crank 33 pivoted on a bracket 34 on the frame. By operating this crank the link and consequently the stud 31 can be 95 raised and lowered.

Mounted on the frame is a stationary plate 35 having a V-shaped slot 36 provided with a socket 37 at the top. Pivoted to this plate on a pivot 39 is a swinging plate 40. 100 This swinging plate has a slot 41, the bottom of which is just wide enough to receive

the stud 31 and the top extends as high as the socket 37, which also is just large enough to receive the stud. This plate 40 is connected by a link 42 with an eccentric 43 on 5 the shaft of the roll 13.

The process is carried out as follows:— The paper to be printed on is moistened slightly before printing. When the stud 31 is at the bottom of the slot 41, the oscillation of the link 42 causes the plate 40 to 10 oscillate and the link 30 to partake of this motion. This obviously swings the arms 29 and 27, vibrates the rod 26 and the blanket 21 between impressions. If, however, the crank 33 is turned to such a position that the stud 31 is held up on the notch 37 it is freed from the control of the slot 41 and positively prevented from vibrating, 15 although the plate 40 continues to operate as usual.

The purpose of this mechanism is to control fully the condition of the blanket and consequently the printing. With the parts in stationary position, it is obvious that the 20 blanket will gradually become hardened on the compressed portions but not in the portions which do not come into contact with the plate but only into the engraved lines thereon. When this action continues to such 25 an extent as to force the ink out of the engraved lines and blur it around the edges the operator will simply move the crank 33 so as to bring the stud 31 down into the bottom of the slot 41 and then the blanket will vibrate 30 and receive impressions on different portions of these surfaces. This will tend to produce a uniform condition of the blanket and then the operator can swing the crank 33 back and allow the printing 35 operation to go ahead with the blanket in its original position until the same condition is met with again. When this shifting action first takes place some of the first impressions may not be perfect and it is only 40 after the result has reached a sufficiently high degree of perfection that the parts are secured in inoperative position so as to continue that character of printing.

Another form in which the invention can 45 be carried out is indicated in Figs. 6 and 7. In this case the numerals 10, 15, 19, 20, 21, 22, 24 and 26 indicate the same elements as in the other sheet, the frame 22 being shown slightly modified as stated above. In this 50 case the rod 26 is connected with a pivoted lever 70 which is operated by a movable rod 71 preferably operated by hand. The other end of the frame 22 is held up by a rod 72 clamped on a bracket 73.

60 The operator moves the rod 71 whenever the prints begin to blur. This simply moves the blanket over to a second position and it is held there by the friction of the parts until the operator changes it. This arrangement is provided so that the operator can

move the blanket over if in his judgment it needs it either with or without the accompanying vibration thereof.

In this case the operator moves the face of the counter a greater or less distance as 70 he may desire, and it is not necessary to bring it back to its original position as in the form shown on the first sheet.

It has been found in practice that by this method the counter can be kept, by a comparatively unskilled operator, in proper condition for the highest class of printing of this difficult type, namely, the printing of both illustrations and reading matter from the same engraved plate and that the moistening of the paper which has also been found to be advisable does not introduce any complications that are not overcome by this invention.

While I describe my invention in connection with the production of work of the above character, upon moistened paper, the invention presents valuable advantages when employed in the production of certain kinds of ordinary die stamping upon dry 90 paper and I do not wish to be limited to the use of my invention on any particular class of intaglio work except as specified in the claims, therefore I do not wish to be limited to the exact procedure described but what I 95 do claim is:—

1. The method of printing which consists in moistening sheets, pressing them one after another between a counter and printing plate while the face of the counter is in one 100 position until the impressions begin to blur and moving the face of said counter to another position between impressions.

2. The method of printing which consists in moistening sheets, pressing them one after another between a counter and printing plate until the counter shows signs of hardening, moving the face of said counter between impressions with the face of the counter in that position, taking some impressions, moving the face of the counter to a second position, and continuing to take impressions.

3. The method of printing which consists in holding the face of a counter in the same 115 position during a plurality of impressions, then vibrating the face of the counter between impressions for a plurality of impressions, and then holding the counter stationary during a plurality of impressions.

4. The method of printing which consists in vibrating the face of a counter during a plurality of impressions, and thereafter holding the counter stationary during a plurality of impressions.

5. The method of printing which consists in pressing sheets between a counter and a printing plate, moving the face of said counter between impressions at will and making impressions with said face in the 130

second position until the counter becomes hardened.

6. The method of printing which consists in pressing sheets between a counter and a printing plate, moving the face of the counter after pressing a number of sheets, printing an additional number of sheets while the face of the counter is in that posi-

tion, moving the face of the counter back to the original position and thereafter printing 10 more sheets with the face in said original position.

In testimony whereof I have hereunto affixed my signature.

JOHN E. WOODBURY.
